UNITED STATES PATENT OFFICE.

ABRAHAM GOLDSHOLL, OF NEW YORK, N. Y.

BELT FASTENER.

Application filed November 11, 1926. Serial No. 147,770.

This invention relates to wearing apparel and has particular reference to closures or fastening means for nether garments such as drawers, bloomers, or the like.

5 Among the objects of the invention is to provide a tightening or closing means for either the waist band or leg portions of a garment that shall be easily applied and manipulated; that may be readily removed 10 from the garment for laundry purposes so as to relieve the belt or tightening feature from being subjected to the laundry fluids and consequent deterioration; that is so constructed as to render it impossible for any 15 other portion of the wearer's garments to become snagged or cut and hence damaged; that is adapted for cheap and rapid production, and other advantages as will be apparent as this description progresses.

20 With the foregoing and other objects in view the invention consists in the arrangement and combination of parts hereinafter described and claimed, and while the invention is not restricted to the exact details of 25 construction disclosed or suggested herein, still for the purpose of illustrating a practical embodiment thereof reference is had to the accompanying drawings in which like reference characters designate the same 30 parts in the several views, and in which—

Figure 1 is a diagram indicating the waist band portion of a garment and the initiation of the insertion of the belt made according to this invention.

35 Fig. 2 is an enlarged front elevation of the overlapping and joined ends of the belt.

Fig. 3 is a longitudinal section on the line 3—3 of Fig. 2.

Fig. 4 is a rear elevation of the joined 40 ends of the belt.

Fig. 5 is a plan view of the blank constituting the guard.

Fig. 6 is a similar view of the blank showing the hook.

45 Fig. 7 is a vertical transverse section on the line 7—7 of Fig. 3.

Fig. 8 is a detail view of the instrument used for inserting the belt into place.

Referring now more specifically to the 50 drawings, I show at 10 a fragment of a garment which may be thought of as the waist portion of a pair of bloomers or the like and provided with one or more gussets 11 and having at the waist line a box-like pleat or pocket 12 with an opening at 13.

14 is a belt in the nature of a flat piece of

tape or its equivalent and made preferably of rubber or some other suitable flexible and elastic material and adapted to be inserted into the pocket at 12 by any suitable means 60 as, for example, a needle or hook 15.

One end of the belt 14 is provided with a hook member 16 comprising a body 16^a and a hook proper 16^b. The body is provided with a plurality of points or spurs 17 shown in flat form in Fig. 6 and which are adapted to be driven through the belt 14 by manipulation of a suitable tool and clinched over on the opposite side, making a permanent attachment.

70 Adjacent to the other end of the belt are disposed a series of fastening members complementary to the hook member 16, the same comprising a series of eyelets 18 or their equivalent suitably spaced from one another and the end of the belt, and each eyelet 18 having associated therewith a crown or guard member 19. As shown the eyelets are of conventional nature or construction, each being forced through the fabric of 80 the belt and clinched thereover on opposite sides.

75 Each guard member is of generally triangular form as shown in Fig. 5 when flat and provided with end and side prongs 20 which, upon the application of a suitable tool, are adapted to be driven through the fabric of the belt and clinched on the opposite side. Coincident with the application of the guard 19 to the belt or prior thereto it 90 is given a convex or humped form as shown in Figs. 3 and 7 adjacent to the eyelet over a part of which the guard projects.

The guard is located between the center of the eyelet protected by it and the extreme 95 end of the belt so that when the hook 16^b of the hook member 16 is passed through any selected eyelet, according to the length or tightness of the belt, the point of said hook 16^b will be housed or shrouded by the 100 guard 19 in such a manner as to render it impossible for the point of the hook to engage with and damage any other part of the garment or hurt the wearer. It is obvious also that the adjustment of the belt as to its 105 effective length may be varied from time to time as may be desired by simply shifting the hook 16^b from one eyelet to another.

110 It is obvious that for the purpose of protecting the rubber or elastic portion from deteriorating effect of laundry fluids it is easy for the belt to be slipped endwise from

its pocket 12 and when the garment is returned from the laundry ready to be worn again the belt may as readily be inserted into the pocket for its intended purpose. The hook 15 is engaged preferably into the first eyelet 18, and with the shank of the hook 15 threaded endwise into and through the pocket the belt will follow as is well understood. The form of the guards 19 is such that during this threading of the belt they will not interfere with the proper slipping or manipulation of the belt. The hook 16^b likewise is preferably so constructed as to offer the least possible resistance to such endwise movement of the belt, it being shown as formed of flat metal so shaped and bent as to provide rounded corners 16^c which facilitate the movement of the hook not only through the pocket, but also into position through the eyelet and into the interior of the guard member 19.

I claim:

In a belt fastener, the combination of a hook member and a series of selective socket members spaced from one another, each of 25 said members being made of a sheet metal stamping and having prongs to engage the belt, the socket member having an eyelet opening communicating with both sides of the belt, the hook member being disposed 30 on one side of the belt and adapted to enter said opening to extend with the point thereof on the other side of the belt, each socket member having an individual metallic guard 35 separate from the eyelet, said guard being spaced from the eyelet and being crowned to form an opening to receive the point of the hook, said opening being transverse to the axis of the eyelet, said opening having its entrance at a side of the eyelet to receive 40 the point of the hook.

In testimony whereof I affix my signature.

ABRAHAM GOLDSHOLL.
